UNITED STATES PATENT OFFICE.

WILLIAM H. MULLINS, OF SALEM, OHIO.

DESIGN FOR A ROOFING-TILE.

SPECIFICATION forming part of Design No. 24,083, dated March 5, 1895.

Application filed September 26, 1894. Serial No. 524,205. Term of patent 7 years.

To all whom it may concern:

Be it known that I, WILLIAM H. MULLINS, a citizen of the United States, residing at Salem, in the county of Columbiana and State of Ohio, have invented and produced a new and original Design for a Roofing-Tile, of which the following is a description, reference being had to the accompanying drawing, in which the figure is a perspective view illustrating my design.

The general purpose of this design is the adornment of roofs for buildings, having as a primary object the production of a roofing tile which is highly ornamental in its appearance, and which affords a most advantageous play for lights and shadows upon its surface.

To this end the essential features of my invention reside in the tile now to be particularly described, and consist in the features hereinafter pointed out.

The illustration forming part of this specification represents a single detached tile constructed in accordance with my invention, being rectangular in outline and ornamented

at its lower end by a bold projection 2 constituting a boss or crocket, which latter merges into a raised rearwardly extending longitudinal body portion 1 of substantially semi-cylindrical form. At either side of said body 1 are arranged longitudinal webs or quirks 4, 4, extending from end to end of the tile and corresponding, one with the other; while the lower extremity of the tile, in addition to crocket 2, terminates in a double or compound ogee 5, constituting an overlapping lip as shown.

Having thus described my tile, what I claim, and desire to secure by Letters Patent, is—

The design for an ornamental roofing tile, substantially as herein shown and described.

In testimony whereof I subscribe my signature in presence of two witnesses.

WM. H. MULLINS.
